UNITED STATES PATENT OFFICE.

CARL CHRISTIAN LARSEN, OF WALKERTON, ONTARIO, CANADA.

STRUCTURAL TOY.

Application filed April 14, 1924. Serial No. 706,456.

To all whom it may concern:

Be it known that I, CARL CHRISTIAN LARSEN, residing at the town of Walkerton, in the Province of Ontario, in the Dominion 5 of Canada, have invented new and useful Improvements in Structural Toys, of which the following is a specification.

The invention relates to structural toys as described in the present specification and 10 shown in the accompanying drawings which form part of the same.

The invention has for its object the provision of means integral with component parts of individual structural toys whereby 15 such parts can be assembled to form the intended toy or model without involving the employment of nails, screws, nuts or analogous fastening means. In this manner structural toys of all descriptions such 20 as working and other models of aeroplanes, vehicles and windmills et cetera, can be readily assembled and taken apart at pleasure.

The invention consists essentially in the 25 provision of projections and corresponding apertures at the several junctures of the component parts of the model or toy; the invention being characterized by the distinctive feature of extending certain projections through one or more of their connecting parts and affixing same together by the 30 insertion of a wedge pin through an aperture in the projection outside of the part to which it is affixed, thus holding the parts 35 firmly together.

For the purpose of illustrating the invention, its embodiment in the model of an aeroplane is shown in the accompanying drawings; however, it will, of course, be 40 readily understood that this is only a typical instance of its application and that it is not intended to in any way restrict the invention to this particular type of structural toy.

45 Referring to the drawings, Figure 1 is a side elevation of the aeroplane with its major parts slightly detached to more clearly illustrate the invention.

Figure 2 is a front view of Figure 1 shown on a reduced scale.

50 Figure 3 is a perspective view of the tail end of the aeroplane with a member

shown detached for the purpose of indicating the manner of its connection.

Figure 4 is a detail of a rudder, extended 55 to constitute a locking bar.

Like numerals of reference designate corresponding parts throughout the figures of the drawings.

In the drawings, the aeroplane body is 60 constructed in three sections; a frontal section representing the bonnet which usually covers the motor; an intermediate section forming the pilot's quarters; and a tail section containing an observer's seat. 65

The bonnet section comprises a pair of flat converging side members, as at 1, having integral projections, as at 2, located at their corners. Contiguous with said side members are flat top and bottom members, 70 as at 3 and 4, likewise provided with projections, as at 5, said members being discernible in Figure 2 of the drawings.

The members 1, 3 and 4 are attached to a frontal plate 6 by insertion of their projections in registering apertures 7 therein. Said members are similarly attached to a vertical strut 8 having apertures, as at 9, for this purpose. 75

Opposing the strut 8 is a further strut 80 10 identical therewith in construction, and between the two is the intermediate section of the body, as at 11, which is composed of flat members connected by interfitting projections and apertures similar to those detailed in the description of the bonnet section. 85

The tail section of the body is likewise composed of flat side members, as at 12, 90 possessing integral frontal and rear projections, as at 13; which frontal projections enter apertures, as at 14, provided in the strut 10, whilst the rear projections are received in apertures 15 of a plate 16.

Contiguous with said side members are flat 95 top and bottom members, as at 17, affixed to the strut 10 and plate 16 by similar interfitting projections and apertures not shown; such members being discernible in Figure 3 of the drawings. 100

Extending rearwardly of the aeroplane body is a rudder 18 which is provided with an integral protracted bar 19 passing through the plate 16 to and through the

- frontal plate 6. The terminus of the bar 19 supports a propeller 20 and is provided with an aperture 21 in which is lodged a wedge-pin 22. This bar serves the purpose of retaining the projections of the frontal, intermediate and rear sections of the body, firmly within their respective aperture connections, thus preventing disengagement of such interlocking parts.
- 10 23 is a tail plane of which there are two, one upon each side of the rudder 18, said tail planes being provided with projections, as at 24, which enters apertures, as at 25, in the side members 12 of the tail section and are securely affixed thereto by insertion of wedge-pins in their apertures 26.
- 15 Each of the struts 8 and 10 are provided with integral shoulders 27 situated in close proximity to their termini and in advance of said shoulders apertures 28 are provided receptive to wedge-pins.
- 20 Supported upon the upper termini of these struts is a wing 29 resting upon the shoulders 27 and secured by insertion of wedge-pins in the apertures 28 of the termini. Similarly a wing 30 is connected to the lower termini of the struts and secured to same by further wedge-pins.
- 25 Connecting together the ends of said wings are a pair of braces 31 having integral shoulders 32 abutting the respective wings and having termini protruding through apertures therein and secured by wedge-pins 33.
- 30 The lower termini of the aforesaid strut 8 is extended beneath the wing 30 to carry an axle 34 which is attached in a similar manner to that of other parts hereinbefore described, and upon this axle are mounted a pair of wheels 35.
- 35 It will be manifest from the foregoing description that whereas this invention is shown in its application to the construction of models or toys from parts already cut, stamped out, or otherwise manufactured, it will be readily understood that this will, without departing from the spirit and scope of the invention, also apply to a hobby wherein the parts may be stamped or printed upon blanks in order that by fretwork such

models or toys may be cut out and later assembled.

What I claim is:—

1. In a toy aeroplane, a body having a series of aligned sections, each composed of flat members, projections extending from the frontal and rear edges thereof, apertured transverse members positioned at the head and tail of the body and between the adjacent ends of said sections so as to receive the respective projections of the said flat members, a bar extending lengthwise of the body with its extremities entering further apertures provided in the transverse members located at the head and tail of the body, a rudder integral with the said bar forming a shoulder to the rear of the tail-end transverse member, and a wedge-pin positioned in an aperture provided in the portion of the bar protruding from the transverse member at the head-end of the body so as to cooperate with the rudder in locking the component parts of the body in their assembled positions.
2. In a toy aeroplane, a body having three aligned sections representing the bonnet, pilot's quarters and tail of the aeroplane, each of said sections being composed of flat members, projections extending from the frontal and rear edges thereof, apertured transverse struts positioned between the adjacent ends of the sections so as to receive certain of the projections of their flat members, an apertured plate positioned at the front of the bonnet section receiving the projections of its constituent members, a similar plate positioned at the rear of the tail section likewise fitted to its constituent members, a bar extending from end to end of the body entering further apertures provided in the said plates, a rudder integral therewith forming a shoulder to the rear of the tail plate, and a wedge-pin lodged in an end of the bar protruding from the frontal plate so as to cooperate with said rudder in locking the component parts of the body in their assembled positions.

Signed at Walkerton, Ontario, Canada, this 24th day of Mch., 1924.

CARL CHRISTIAN LARSEN.
